UNITED STATES PATENT OFFICE.

EDWARD B. THOMAS, OF SAN FRANCISCO, CALIFORNIA.

CENTER-DRAFT BELL-BOTTOM BASE-BURNER HEATING-STOVE.

SPECIFICATION forming part of Letters Patent No. 392,894, dated November 13, 1883.

Application filed November 22, 1887. Serial No. 255,935. (No model.)

To all whom it may concern:

Be it known that I, EDWARD B. THOMAS, a citizen of the United States, residing in the city and county of San Francisco, and State 5 of California, have invented a new and useful Center-Draft Bell-Bottom Base-Burner Heating-Stove, of which the following is a specification.

My invention relates to improvements in 10 stoves, which will be understood by reference to the accompanying drawings.

Figure 1 is a view of a stove embodying my 15 improvements, the same being partly in vertical section and partly in elevation. Fig. 2 is a sectional view taken on the line $x-x$, Fig. 1; and Fig. 3 is a view of one of the ash-pans removed.

The following is the construction of the same:

A represents a drum, composed of sheet-iron, in appearance like the drum upon the top of 20 a stove of ordinary construction; B, the magazine, of cast-iron, with cover C of ordinary construction; D, the outer case of the stove, made of such metal as the use of the stove may require, either casting or sheet metal; E, the 25 grate, of casting, such as is usually employed in that class of construction; F, the center cone-shaped chamber, generally of cast-iron; G, the smoke or draft pipe generally employed in heating; H, the upper connecting-pipe for connecting the pipe G with the drum A. I represents the damper to open and close the circulation or draft through the connecting-pipe H when required. J represents the ash-pans, which are of a semicircular form and supported 30 upon the usual base-plate in the ordinary manner. K represents the shaker. L represents the cold-air-supply pipes. M represents the damper in the pipe G. G' represents the bell-shaped outer shell or case of the stove; H', the 35 cap of the pipe G to prevent the fuel from dropping into the same. P represents the dividing-bar which directs the ashes into the ash-pans.

The following is the operation of my improvements in stoves: The fuel is placed upon 45 the grate around the cone-shaped chamber, and the current of air arising through the fuel or grate passes up to the top of the cone within the fire-chamber and is drawn down through 50 the pipe G. Thus, in addition to the reverberatory effect produced, an increase of heat-

ing-surface is secured equal to the surfaces of the cone-shaped chamber F and pipe G.

It should be observed that the chamber F, which I have here illustrated as of a truncated 55 conical form, is closed at its upper end, or, in other words, has no communication with the fire-chamber. The cold-air pipes L are designed to conduct cold air into this chamber F and discharge within the same, near the upper portion thereof, the air thus introduced coming in contact with the heated walls of the said chamber and also the draft-flue G, as well as intermingling with the radiated heat from both, after which by the fresh supply of cold 60 air a draft is caused, which forces the heated air down within the conical-formed chamber, 65 where it is discharged into the room where the stove is located.

I have found that the cold-air pipes may in 70 some cases be dispensed with, and when an oblong or oval chamber has been employed and such chambers multiplied a very good result is had; but I prefer to use the cold-air tubes, 75 as I have found by experience that a better result is accomplished by the employment of such.

In placing the fuel in the stove it is fed 80 through the feed-pipe B. The damper I being open and the damper M closed, the direct upward draft is thus established. As soon as the fire is properly burning, the damper M is opened and the damper I closed. The current of hot air is thus carried down through 85 the pipe G, allowing the heat to radiate from the pipe G and the cone-shaped chamber F. The increase of heating-surface, in addition to the air-supply from the pipes L, more than doubles the heating effect with the same amount of fuel.

I do not desire to confine myself to a conical form central chamber, as the same principle of invention may be carried out by constructing the chamber in an oblong or oval form or with an under hot-air chamber of any description where the central downward draft is secured and the reverberatory effect described is produced.

Having thus described my invention, what I claim, and desire to secure by Letters Patent, 95 is—

1. In a stove, the combination of the central

cone-shaped chamber, the smoke or draft pipe having one end arranged within the said chamber, the cap on the said pipe above the chamber, and the cold-air pipes having one end opening within the chamber and the opposite end opening beneath the stove, substantially as specified.

2. In a stove, the combination of the cone-shaped chamber arranged therein, the draft-pipe G, having one end passing upwardly through the chamber and provided with a cap, H, the pipe H', connecting the upper portion of the stove-body with the draft-pipe and having a damper, as I, and the damper M in the said draft-pipe below the point of connection of the pipe H, all substantially as specified.

3. In a stove, the combination, with the outer shell or casing, of an open-bottom air-chamber arranged therein and closed from communication with the fire-chamber and at the top, and a draft-pipe having one end arranged within said air-chamber, closed from communication therewith, and open to communication with the fire-chamber, and cold-air pipes passing into the said air-chamber and opening near the top thereof, substantially as specified. 20 25

EDWARD B. THOMAS.
